UNITED STATES PATENT OFFICE.

LOUIS JAY GERSON, OF PALISADES, NEW YORK, ASSIGNOR OF ONE-HALF TO FRANK W. WOOD, OF NEW YORK, N. Y.

MOTOR-SUPPORTING BOARD.

1,413,219.

Specification of Letters Patent. Patented Apr. 18, 1922.

Application filed April 8, 1920. Serial No. 372,316.

To all whom it may concern:

Be it known that I, LOUIS JAY GERSON, a citizen of the United States, residing at Palisades, in the county of Rockland and 5 State of New York, have invented certain new and useful Improvements in Motor-Supporting Boards, of which the following is a specification.

This invention relates to motor supporting boards for phonographs, the object thereof being the provision of an improved motor supporting board, which may be readily raised and lowered to permit inspection of the motor carried thereby at the 10 under side thereof, and one object of the invention is the provision of a metal motor board which can be readily supported for swinging movement and for quick detachment in a phonograph cabinet, particularly 15 of the form shown and described in my contemporaneously pending application for metal phonograph structure, Serial No. 371,711, filed April 6, 1920, and which will be simple in construction, inexpensive to 20 make and very efficient in use.

In the drawings accompanying and forming part of this specification, Fig. 1 is a top view of a phonograph structure substantially similar to that shown in my said 30 contemporaneously pending application; Fig. 2 is a vertical sectional view of the upper portion of said cabinet; Fig. 3 is a perspective view partly broken away of the motor board supporting frame; Fig. 4 is a 35 perspective view of this improved motor supporting board; Fig. 5 is a detail sectional view of one catch or fastening means which may be used to secure the motor supporting board in place; and Fig. 6 is an 40 enlarged detail sectional view of one corner of the motor supporting board shown in Fig. 4.

Similar characters of reference indicate corresponding parts in the several figures 45 of the drawings.

The cabinet shown herein is of metal form, and is similar to that shown and described in my contemporaneously pending application, and therefore a detailed description thereof is not deemed necessary 50 in this case. In brief, it consists of metal corner posts and side panels, all connected together by concealed fastenings.

To the side panels is connected by con- 55 cealed fastenings a finishing moulding 2, to

which is hinged a top 3. This moulding is provided with an inwardly extending flange 4, upon which rests the motor supporting frame 5, which is likewise similar to that shown and described in my said pending application, and to which motor supporting frame 5 the tone arm 6 and the metal horn 7 are secured in the manner shown. This motor supporting frame 5 is suitably cut out as at 8, to provide an opening for the 60 reception of the motor supporting board, and the edges of the frame around the opening are provided with downwardly turned flanges 9, the two side edges being provided with oppositely projecting pins 10. 70 The front side of the motor supporting frame 5 is also provided with a pair of pins 11 forming stops to limit the downward movement of the motor supporting board. 75

At each side of the supporting frame is located a suitable fastening 12 shown as a spring catch having a projecting bolt 13 adapted to project into openings 14 at each side of the motor supporting board 15 to 80 lock it in its normal operating position. This motor supporting board like the motor supporting frame is shown formed of metal and it likewise is provided with downwardly flanged edges 16, the front flanged 85 edge having suitable notches 17 to receive the pins 11 while the two side flanged edges are provided with a pair of diagonal slots 18 terminating in enlarged openings 19 for the reception of the pivot pins 10 of the motor 90 supporting frame. The motor supporting board has secured thereto at its under side the usual motor 20, the spindle of which projects through the central opening 21 of the motor supporting board and carries the 95 revolving disk or table.

The motor supporting board 15 is readily insertable into the opening 8 of the supporting frame 5 by so inserting the board 15 that the pins 10 will pass into the diagonal slots 18 of the board 15 whereupon the board may be easily swung upon the pivots upward to permit access and inspection and oiling of the motor or the board can be readily lifted together with the motor from 105 the machine when the handle which winds up the motor is first detached.

The various details may be more or less changed without departing from the spirit or scope of the present improvement. 110

I claim as my invention:

1. In a phonograph cabinet the combination of a motor board supporting frame provided with depending flanges forming an opening, and a motor supporting board adapted to fit said opening and having downwardly projecting flanges adapted to cooperate with said depending flanges.
2. In a phonograph cabinet the combination of a motor board supporting frame having a motor board opening, a motor supporting board adapted to fit the opening, one of said members having one or more pivot pins and the other one or more diagonal open slots for the reception of said pins, thereby to permit the ready engagement and disengagement of the pins with the slots.
3. In a phonograph cabinet the combination of a motor board supporting frame having a motor board opening, a motor supporting board adapted to fit said opening, one of said members having one or more pivot pins and the other one or more diagonal open slots for the reception of said pins, thereby to permit the ready engagement and disengagement of the pins with the slots, said diagonal slots terminating each in an enlarged opening.
4. In a phonograph the combination of a motor supporting frame having a motor board opening provided at opposite sides with a pair of pivot pins, and a motor supporting board having at opposite sides diagonal slots adapted to receive said pins, said slots extending to the edge of said board to form open slots, thereby to permit the ready engagement of the pins therein.
5. In a phonograph cabinet the combination of a motor supporting frame having a motor board opening provided at opposite sides with a pair of pivot pins, and a motor supporting board having at opposite sides diagonal slots adapted to receive said pins, said slots terminating each in an enlarged opening and extending to the edge of said board to form open slots, thereby to permit the ready engagement of the pins therein.
6. In a phonograph cabinet the combination of a motor supporting frame having a motor board opening provided at opposite sides with pivot pins, a motor supporting board having a pair of flanged sides provided with diagonal slots adapted to receive said pins, said slots opening at the lower edges of said flanged sides whereby the motor supporting board may be detached from said pins.
7. A phonograph cabinet having a motor board supporting frame having depending flanges, a pair of opposed pins carried by a pair of said flanges, a motor supporting board also having depending flanges, and diagonal slots located in a pair of said last flanges and terminating at their upper ends in enlarged openings and at their lower ends at the lower edges of said flanges and adapted to receive said pins thereby to permit the motor supporting board to be swung from the pivots or to be readily detached therefrom.
8. A phonograph cabinet having a motor board supporting frame having depending flanges, a pair of opposed pins carried by a pair of said flanges, a motor supporting board also having depending flanges, diagonal slots located in a pair of said last flanges and terminating at their upper ends in enlarged openings and at their lower ends at the lower edges of said flanges and adapted to receive said pins thereby to permit the motor supporting board to be swung from the pivots or to be readily detached therefrom, and means carried by the motor supporting frame for limiting the downward movement of the motor supporting board.
9. A phonograph cabinet having a metal motor board supporting frame provided with downwardly bent flanges forming a motor board opening, a pair of said flanges having inwardly projecting pivot pins, and a motor supporting board having downwardly projecting flanges provided with slots for the reception of said pins whereby the motor board may be swung upwardly.
10. A phonograph cabinet having a metal motor board supporting frame provided with downwardly bent flanges forming a motor board opening, a pair of said flanges having inwardly projecting pivot pins, and a motor supporting board likewise formed of metal having downwardly projecting flanges provided with slots for the reception of said pins whereby the motor board may be swung upwardly, said slots being located diagonally to the lower edges of said flanges.
11. A phonograph cabinet having a metal motor board supporting frame provided with downwardly bent flanges forming a motor board opening, a pair of said flanges having inwardly projecting pivot pins, and a motor supporting board likewise formed of metal having downwardly projecting flanges provided with slots for the reception of said pins whereby the motor board may be swung upwardly, said slots being located diagonally to the lower edges of said flanges and having enlarged openings at their upper ends and opening at the free edges of the flanges.

Signed at New York, in the county of New York and State of New York, this third day of April, 1920.

LOUIS JAY GERSON.
